United States Patent Office.

WILLIAM CAVEN, OF CINCINNATI, OHIO, ASSIGNOR TO REDWAY AND BURTON, OF SAME PLACE.

Design No. 2,714, dated August 6, 1867.

DESIGN FOR A CANNON STOVE.

The Schedule referred to in these Letters Patent and making part of the same.

TO WHOM IT MAY CONCERN:

Be it known that I, WILLIAM CAVEN, of Cincinnati, in the county of Hamilton, and State of Ohio, have invented a new Design for a Cannon Stove, which design is represented in the accompanying illustration, which forms a part of this specification.

I claim, and desire to secure by Letters Patent—

The design for a cannon stove, substantially as represented in the accompanying illustration.

In testimony of which invention I hereunto set my hand.

WM. CAVEN.
